CLAIM

The ornamental design for a golf club, or similar article, substantially as shown and described.

DESCRIPTION

FIG. 1 is a front elevational view of a golf club showing my new design;

FIG. 2 is a top plan view of the golf club of FIG. 1;

FIG. 3 is a bottom plan view of the golf club of FIG. 1;

FIG. 4 is a back elevational view of the golf club of FIG. 1;

FIG. 5 is an end elevational view of the golf club of FIG. 1;

FIG. 6 is a rear elevational view of the golf club of FIG. 1;

FIG. 7 is a broken away view of the artistically designed portion of the shaft taken from Section 7—7 of FIG. 1; and,

FIG. 8 is a broken away cross-sectional view of the same section of the shaft taken on line 8—8 of FIG. 7. The characteristic feature of my design resides in the particular arrangement of circular embossments on the shaft portion as shown.
